STARCH TABLING SYSTEM

Harry W. Curry, Kansas City, Mo., assignor to
 International Patents Development Company,
 Wilmington, Del., a corporation of Delaware

Application May 16, 1932, Serial No. 611,624

1 Claim. (Cl. 127—26)

This invention relates to the operation of tabling mixtures of starch gluten and water, and the manufacture of starch from corn, for separating the starch and the gluten. The starch settles on the tables and the gluten being lighter, tails off with most of the water from the ends of the tables. As a consequence the velocities of the flow over the tables, controlled by the quantity of the mixture delivered to each of such tables per unit of time, is an important feature in obtaining separation of the starch and gluten, one from the other, in as complete manner as possible. Hence, the maintenance of uniform velocities over all of the tables in the factory, which tables may be at a number of different elevations and at different distances from the sources of supply, is a matter of great importance in insuring as complete a separation as possible.

The primary object of this invention is to make possible, by certain novel and improved arrangements and procedures, the maintenance of such uniform tabling conditions. A further object is to provide a system of operation that will obviate the necessity of individual control of the flow to the tables severally. That is, the purpose is to automatically obtain uniformity of flow of the starch and gluten mixture over the tables which will result because of the free and unobstructed overflow at the lower ends of the tables if the rate of supply is constant.

The invention is illustrated in a preferred embodiment in the accompanying drawing wherein:

Fig. 1 is a fragmentary sectional view, taken longitudinally of the tables showing the tabling arrangements at two elevations; and

Fig. 2 is a cross sectional view of the tables at one elevation and their feeding arrangements.

Referring to the drawing: A designates a set of starch tables, and B another set at a lower elevation. These tables ordinarily are shallow troughs about 110 feet long with a pitch of five inches from end to end, and are divided into channels 10 by longitudinally extending strips 11, the channels being ordinarily about two feet wide.

Arranged above the tables at each elevation is a supply tank, two tanks being shown, designated C and D, respectively. Each tank is provided with an overflow pipe which extends to the tank at the lower elevation. For example, tank C is provided with an overflow pipe 12, preferably with a funnel 13 at its upper end. This pipe discharges surplus liquor in tank C to tank D, so as to maintain the liquor in the vessel at uniform level indicated at c. The liquor is supplied to vessel C through pipe 14. The vessel is provided with an outlet pipe 15, controlled by a valve 16. The outlet pipe leads to a common header 17 for the

upper set of tables A. A series of perforated headers 18 are arranged below the header 17, one header 18 over each of the tables A, that is, over each set of channels 10. The liquor is sent from header 17 through pairs of branch pipes 19, 19 which are connected with the headers 18 near the extremities of the headers. These branch pipes are provided with valves 20. A valve connection 21 is shown between outlet pipe 15 and the overflow pipe 12 for clean-out purposes. Preferably the headers 17 are provided at their extremities with air vent pipes 22 which extend above the normal level of the liquor in the supply vessels.

The arrangements in connection with tables B and supply vessel D are the same as described in connection with tables A and supply vessel C, and are given corresponding numerals. The overflow pipe 12 from vessel D leads to the supply vessel (not shown) at the next lower level.

It will be understood that the drawing is diagrammatical. No effort has been made to show the pipes, tanks, and tables in their proper proportions.

By the arrangements shown and described the quantities of starch and gluten liquor delivered to the several channels of each of the starch tables will be uniform, or substantially so, regardless of the elevation of the table or its distance from the source of supply. The factor of friction in the headers 17 is compensated by a proper setting of the valves 20. Once these valves have been set, the system operates automatically by gravity. It would be understood that the valves in the pipe sections 21 are automatically closed.

I claim:

In combination with two starch tables arranged at two different elevations and comprising sets of adjacently arranged channels, a pipe system for gravity distribution of starch and gluten liquor to the tables and a control means for feeding said liquor to the tables at a substantially uniform rate comprising a supply vessel above each table, an overflow pipe in each supply vessel for maintaining the starch and gluten liquor at the same constant level in each vessel, the overflow pipe in the upper vessel leading to the lower vessel, a supply pipe for supplying starch and gluten liquor to the upper vessel, a valve in the bottom of each supply vessel, a main header for each supply vessel connected with said valve, each of said main headers extending horizontally above the upper end of each table and substantially parallel with said upper end, air vent pipes extending from the main headers to a point above the normal level of the respective supply vessels, and similarly positioned separate headers, provided with discharge openings for the several sets of adjacently arranged channels, said separate headers being supplied at opposite ends from the main header.

HARRY W. CURRY.
